Primary Examiner — Elizabeth J Oswecki(74) *Attorney, Agent, or Firm* — Albert Haegele; Leyendecker & Lemire, LLC**CLAIM**

The ornamental design for a stylized Christmas tree, as shown and described.

DESCRIPTION

FIG. 1 is a top, side, perspective view of a stylized Christmas tree showing my new design;

FIG. 2 is a side elevational view thereof;

FIG. 3 is a top plan view thereof; and,

FIG. 4 is a bottom plan view thereof.

Broken lines shown in the drawings illustrate unclaimed matter, form no part of the claimed design, and are provided for context only.

All surfaces not shown form no part of the claimed design.
